US00D452333B1

(12) **United States Design Patent** (10) Patent No.: **US D452,333 S**
Merrick (45) Date of Patent: **** Dec. 18, 2001**

(54) **SAREPTA FENCE POST FINIAL**
(75) Inventor: **Richard James Merrick, Alda, NE (US)**
(73) Assignee: **T.M.C., Inc., Alda, NE (US)**
(**) Term: **14 Years**
(21) Appl. No.: **29/116,405**
(22) Filed: **Mar. 21, 2000**
(51) LOC (7) Cl. **25-01**
(52) U.S. Cl. **D25/135**
(58) Field of Search **D25/135; 256/65, 256/66; 52/300, 301**

(57) **CLAIM**

The ornamental design for a sarepta fence post finial, as shown and described.

DESCRIPTION

FIG. 1 is a front perspective view showing the sarepta fence post finial of the present invention.

FIG. 2 is a top plan view showing the sarepta fence post finial of the present invention.

FIG. 3 is a bottom plan view thereof;

FIG. 4 is a front elevational view thereof;

FIG. 5 is a right side elevational view of FIG. 4; and,

FIG. 6 is a left side elevational view of FIG. 4.
